PUMPING UNIT

James R. Henry and Roy P. Downing, Tulsa, Okla.

Application January 3, 1939, Serial No. 249,177

4 Claims. (Cl. 74—50)

This invention relates to a pumping unit particularly for reciprocating the sucker rods of an oil or like well, and has for its principal object to provide a simple and inexpensively constructed unit of this character which is adapted for efficiently operating the rods with a relatively small power.

Other objects of the invention are to provide a pumping unit constructed to effect true vertical lift of the polish rod, thereby avoiding bending and whipping stresses which tend to failure of the rods and wear of the stuffing box; to provide a smooth acting rotary mechanism directly connected with the rods; and to provide the rotary mechanism with an effective counterbalance.

In accomplishing these and other objects of the invention, as hereinafter set forth, we have provided improved details of structure, the preferred forms of which are illustrated in the accompanying drawings, wherein:

Fig. 1 is a perspective view of a pumping unit embodying the features of the present invention.

Fig. 2 is a front elevational view of the unit.

Fig. 3 is a side elevational view with the polish rod actuating rotor shown in section.

Fig. 4 is a detail perspective view of the polish rod actuating rotor, parts of which are broken away to better illustrate the construction thereof.

Fig. 5 is a perspective view of the cross head and its connecting link whereby the polish rod is connected with the actuating rotor.

Fig. 6 is a fragmentary elevational view, partly in section, of a modified form of pumping unit.

Referring more in detail to the drawings:

1 designates a pumping unit constructed in accordance with the present invention, which includes a frame 2 adapted to be mounted on a sub-frame or other supporting structure 3 adjacent the side of a well, indicated by the casing head 4. The frame 2 is preferably formed of structural members and includes corner posts 5 connected at their upper and lower ends by longitudinal members 6—7 and side members 8—9 to form a substantially rectangular framework mounting a platform 10 for supporting a gear reduction unit 11 and a prime mover 12, the prime mover 12 being connected with the power input shaft 13 of the reduction gear, as clearly shown in Figs. 1 and 2.

Extending laterally from the lower member 1 at the front of the frame, are spaced arms 14 and 15, which project slightly beyond the axis of the well to mount pairs of vertical posts 16—17 and 18—19 connected at their upper ends by bearing supports 20 and 21. Mounted on the bearing supports are bearing brackets 22 and 23 rotatably mounting an extension 24 of the power output shaft of the reduction gear unit. The

lateral arms 14 and 15 are braced with respect to the member 1 by diagonals 25 and 26 which cooperate with the bearing supports in maintaining fixed spaced relation of the pairs of vertical posts 16—17 and 18—19 so that they form fixed vertical guideways 27 and 28 at the respective sides of the well axis.

Fixed to the shaft 24, at a point between the bearings 22 and 23, is a rotor 29 for effecting reciprocation of the polish rod 30 of the well 4, as later described. The preferred form of rotor is best illustrated in Fig. 4, and includes a spaced pair of circular disks 31 and 32 eccentrically connected by an elongated hub 33 which extends

15 radially of the disks and is provided with a plurality of shaft receiving openings 34 extending therethrough in parallel, spaced, radial relation with the axis of the disks. The openings 34 are provided with keyways 35 adapted to engage a key 36 carried by the shaft 24, so that the rotor may be mounted eccentrically on the shaft at selected degrees of eccentricity, depending upon which of the openings 34 through which the shaft is extended.

20 Extending laterally in facing relation about the peripheries of the disks are flanges 37 and 38 forming circular tracks 39 and 40 spaced apart, as at 41, to accommodate a pitman or connecting link 42, later described. The disks 31 and 32 are preferably provided with registering cutout portions 43 and 44 located diametrically opposite the hub 33 so as to facilitate assembly of the polish rod connecting mechanism, now to be described.

25 The connecting mechanism includes the link 42 and a cross head guide 45. The cross head guide is shown as comprising a substantially U-shaped body having upwardly directed arms 46 and 47 connected by a cross bar 48 having a rod or shank 49 to which the polish rod 30 is connected by a suitable coupling 50, as shown in Figs. 1 and 2. One end of the link 42 extends between the arms 46 and 47 and is pivotally connected therewith by a shaft 51 secured from

30 movement in the arms 46 and 47 by set screws 52 and 53. The shaft 51 has projecting ends which mount rollers 54 and 55 operable in the guideways 27 and 28, previously referred to. The rollers 54 and 55 are of suitable diameter so that the peripheral faces 56 thereof are adapted to rollingly engage the respective sides of the guideways to retain the cross head directly over the axis of the well when the cross head is being reciprocated by the rotor 29. The link 42 extends through the space 41 and its upper end carries a cross shaft 57 mounting rollers 58 and 59 in such a position that the peripheral faces 60 thereof engage the circular tracks of the rotor, as shown in Figs. 1 and 3.

35 42 extends through the space 41 and its upper end carries a cross shaft 57 mounting rollers 58 and 59 in such a position that the peripheral faces 60 thereof engage the circular tracks of the rotor, as shown in Figs. 1 and 3.

40 Fixed to the shaft 24, preferably at a point

thereon between the inner bearing 23 and the speed reduction unit 11, is an arm 61 extending opposite to the maximum off center side of the rotor. Adjustably mounted on the arm is a sector-shaped counterweight 62 having flanged guides 63 and 64 engaging the respective sides of the arm. The weight is adjustably secured to the arm by fastening devices, such as bolts 65, extending therethrough and through a registering slot 66 in the arm, as best shown in Fig. 2. It is thus obvious that the weight is adjusted radially with respect to the shaft to vary the counterbalancing effects thereof as required to relieve the major thrusts acting on the rotor incidental to lifting of the rods.

The form of the invention shown in Fig. 6 employs a modified form of rotor. This rotor 67 consists of a single eccentric disk 68 having laterally directed peripheral flanges 69 and 70 forming tracks 71 and 72 for rollers 73 and 74, the rollers being pivotally connected to links 75 and 76 having their lower ends pivotally connected with a cross shaft 77 similar to the cross shaft 51, previously described in connection with the preferred form of the invention. The construction is otherwise identical to that illustrated and described in connection with the preferred form of the invention.

The operation of a pumping unit constructed as described, and mounted in position relatively to a well 4, is as follows:

The rotor 29 is adjusted on the shaft 24 to give the desired stroke of the polish rod. This is effected by positioning the shaft 24 in one of the openings 34 and securing the rotor thereon by the key 36. The cross head assembly is then suspended in guided relation with the guides 27 and 28 by the rollers 58 and 59 which bear upon the circular tracks 39 and 40. The rod or shank 49 is then coupled with the polish rod. When thus connected the axis of the rollers 58 and 59, as well as the axis of the guide rollers 54 and 55, are positioned in the same axial plane as that of the polish rod so that the weight of the rods and well fluid being lifted thereby acts directly in a perpendicular direction. The counterbalance 62 is then adjusted on its supporting arm to give the desired counterbalancing effect of the rotor and the load lifted thereby. When the prime mover 12 is placed in operation, the shaft 24 is operated at a reduced speed to effect gyration of the rotor, as shown by the arrow in Fig. 2. Actuation of the rotor with the rollers 58 and 59 riding on the tracks thereof effects rise and fall of the cross head to cause vertical reciprocation of the rods so that a direct lift is effected thereon during the entire rotational cycle of the eccentric rotor. The link 42, being pivotally connected with the cross head, allows the rollers 58 and 59 to float freely on their circular tracks so as to compensate for any misalignment and to allow freedom of movement thereof to accommodate the link incidental to the thrusts of the loads acting thereon, as shown by the dotted lines in Fig. 2.

The form of the invention shown in Fig. 6 operates in exactly the same manner as described in connection with the preferred form of the invention.

From the foregoing it is obvious that we have provided a pumping unit which is of simple, inexpensive construction, and adapted for efficient-

ly operating the pump rods of a well with a relatively small power unit. It is also obvious that we have provided a true vertical lift of the polish rod and thereby avoid bending and whipping stresses which ordinarily cause failure and breakage of the rods and wear on the stuffing box through which they operate.

What we claim and desire to secure by Letters Patent is:

1. In a pumping apparatus of the character described, a supporting frame having a lateral extension, spaced posts carried by said extension and forming a vertical guideway, a bearing carried at the upper ends of said posts, a shaft 15 rotatably mounted in said bearing, a rotor eccentrically mounted on said shaft having an eccentric track, a roller mounted on said track, a link pivotally suspended from the axis of said roller, a cross head having guide means operating in said guideway, means pivotally connecting the cross head with said link, and means connecting the cross head with a polish rod.
2. In a pumping apparatus of the character described, a supporting frame having a lateral extension, spaced pairs of posts carried by said extension and forming vertical guideways, bearings carried at the upper ends of said posts, a shaft 20 rotatably mounted in said bearings, a rotor eccentrically mounted on said shaft between said pairs of posts and having eccentric tracks spaced apart to accommodate a link therebetween, rollers mounted on said tracks, a shaft connecting the rollers, a link pivotally suspended from the connecting shaft and depending between said spaced apart tracks, a cross head having guide means operating in said guideways, means pivotally connecting the cross head with said link, and means connecting the cross head with a polish rod.
3. In a pumping apparatus of the character described, a support, a shaft rotatably mounted on the support, a rotor including spaced disks having inwardly facing flanges to form trackways and a hub mounted on said shaft and spacely connecting said disks, spaced guideways at the outer side faces of the respective disks, a cross head reciprocably mounted in said guideways, rollers on said trackways, a shaft connecting the rollers, a link suspended from the roller connecting shaft and depending between the spaced disks, means pivotally connecting said link with the cross head, and means carried by the cross head for connecting the cross head with a polish rod.
4. In a pumping apparatus of the character described, a supporting frame having a lateral extension, spaced pairs of posts carried by said extension and forming vertical guideways, bearings carried at the upper ends of said posts, a shaft 55 rotatably mounted in said bearings, a rotor including spaced disk portions eccentrically mounted on said shaft between said pairs of posts and having eccentric tracks, rollers mounted on said tracks, a shaft connecting the rollers, guide rollers mounted in said guideways, a shaft connecting the guide rollers, a link extending between the disk portions and connecting said shafts, and means connecting the guide roller shaft with a polish rod.

JAMES R. HENRY.
